UNITED STATES PATENT OFFICE.

ROBERT C. BROOKS, OF SAVANNAH, GEORGIA.

CAR FENDER.

Application filed October 21, 1922. Serial No. 596,119.

To all whom it may concern:

Be it known that I, ROBERT C. BROOKS, a citizen of the United States of America, and a resident of Savannah, county of Chatham, and State of Georgia, have invented certain new and useful Improvements in Car Fenders, of which the following is a full and clear specification.

This invention has relation to that type 10 of car fender in which a scoop or pickup member is lowered to the roadbed when the apparatus is put into operation, and the object is to provide a simple mechanism whereby the operation will take place automatically whenever there is an emergency application 15 of the air-brake of the car, the construction being such that the air exhausted from the air-brake system by the emergency application is utilized for putting the fender into operative position, as more fully hereinafter set forth.

In the drawing annexed—

Fig. 1 is a plan view of a car, partly broken away, showing one way of applying 25 my invention;

Fig. 2 is a vertical sectional view of the same showing the fender parts in non-use position;

Fig. 3 is a similar view showing the fender mechanism tripped, with the pickup member in position for operation;

Fig. 4 is a detail longitudinal sectional view of the piston and cylinder arrangement for tripping the fender.

Referring to the drawing annexed, it will be observed that I have shown my invention as applied to a standard fender of the pickup type, which embodies a trip-apron 5 affixed to a rock-shaft 6 having a radial arm 7 which is connected by a long link rod 8 to an upstanding lever 9 carried by the tiltable pickup member 10, the construction being such that when the trip-apron 5 is swung rearwardly by an obstacle on the track the rock-shaft will be rotated over forwardly far enough to throw arm 7 over center, whereupon the retractile coil-spring 11 will automatically tilt the pickup member to bring its forward edge down upon the rails in position to pick up any obstacle that may pass under the trip-apron 5.

To apply my invention to this type of fender, I extend upwardly one of the vertical bars or straps of the trip-apron to form an upstanding rod 12, and I affix to the under side of the car body, at a point to the

rear of the upstanding rod 12, a cylinder 13 which encloses a piston 14 whose rod 15 extends out through the front head of the cylinder and has its forward end in contact 60 with or nearly in contact with the rear face of the aforesaid upstanding rod 12. A coil-spring 16 within the cylinder normally holds the piston and its rod at its rear, inoperative position. A pipe 17 extends from the rear head of the cylinder to the emergency exhaust of the usual pilot-valve 18 of the air-brake mechanism, so that upon making an emergency application of the air-brake 70 of the car (which emergency application involves, as is well known, liberation of the air from the emergency train-pipe system), the air that is usually discharged into the atmosphere will be discharged into said pipe 17. It is usual, in the standard safety car equipment of today, to provide for an emergency operation of the pilot-valve automatically whenever the operator removes the weight of his hand from the controller-handle, shown at 19 in my drawing, but it 80 will be understood that my invention contemplates broadly the use of waste emergency air for putting the fender into active position without regard to the manner in which the emergency application of the 85 brake is made.

It will be understood that when the emergency waste air is thus thrown into the rear end of the cylinder 13, the piston therein will be forced forwardly against the action 90 of its spring 16 and thus tip the upper end of the rod 12 forwardly, in the same manner it is actuated when the trip-apron 5 is swung rearwardly by striking against an object on the track, so that with my appliance the 95 fender is operated in precisely the same way it is when it is put into action by an obstacle on the track. After an actuation of the fender, the trip-apron and pickup member are returned, as usual, manually, but 100 the piston 14 is returned automatically by the spring 16, suitable openings 20 and 21 being provided for the escape of the confined air, one of these openings being in the cylinder 13 and the other being in pipe 17. 105 These openings 21 and 20, it will be understood, are not of sufficient area to permit sufficient air to escape to interfere with the quick and effective operation of the piston, but they are of sufficient area to not only 110 permit the normal restoration of the piston to its rear position, but also to permit sur-

plus air to escape to the atmosphere, to thereby prevent my appliance from interfering with proper operation of the emergency brake mechanism, it being necessary, 5 as is obvious, to permit free escape of the air from the train-pipe whenever an emergency application is made. It is desirable that the opening 21 in the pipe 17 shall be merely a bleed opening, while the opening 10 20 in the cylinder may be much greater in diameter to permit free escape of the air from the cylinder after the piston has moved far enough forwardly to trip the fender.

I claim:

- 15 1. In combination with a railway car equipped with an air-brake system, a fender thereon and means for holding it out of action, and pneumatic means for putting the fender into action embodying a pipe connected to the emergency air exhaust port of the controller pilot-valve of the brake system.
- 20 2. In combination with a railway car equipped with an air-brake system, a fender embodying a tripping mechanism adapted to be operated by an obstacle on the road-bed, and a pneumatic appliance for automatically actuating the said tripping mechanism embodying a pipe connected to the 25 emergency exhaust port of the controller pilot-valve of the brake system.
- 30 3. In combination with a railway car equipped with an air-brake system, a fender appliance for the car embodying a tilt-able pickup member and a depending trip-apron, said trip-apron having an upstanding member, a cylinder attached to the car, a piston in the cylinder having a rod adapted to actuate said upstanding member to thus 35 actuate the tripping mechanism, and a pipe connecting said cylinder to the emergency exhaust of the air-brake system to thus ensure actuation of the piston whenever there is an emergency application of the brake.
- 40 4. In combination with a railway car equipped with an air-brake system, a fender

appliance for the car embodying a tiltable pickup member and a depending trip-apron, said trip-apron having an upstanding member, a cylinder attached to the car, a piston in the cylinder having a rod adapted to actuate said upstanding member to thus actuate the tripping mechanism, and a pipe connecting said cylinder to the emergency exhaust of the air-brake system to thus ensure actuation of the piston whenever there is an emergency application of the brake, said cylinder and pipe being provided with escape openings, for the purpose set forth.

5. In combination with a railway car 60 equipped with an air-brake system, a fender thereon and means for holding it out of action, and pneumatic means for putting the fender into action embodying a pipe connected to the emergency air exhaust of the 65 air-brake system and an actuating cylinder connected to this pipe, this cylinder being provided with a port to permit free escape of the air after the fender has been actuated to thus avoid interference with the operation of the brake system.

6. The combination with a railway car equipped with an air-brake system, of a fender thereon and spring means for holding the fender normally out of action and 75 adapted to be reversed in order to normally hold the fender in action, a tripping means adapted to be actuated by a body on the track and functioning to reverse the action of said spring means to thus normally throw the fender to the track, and additional means for actuating the tripping means embodying a pneumatic motor and an air-supply pipe for actuating the same, said air-supply-pipe being connected to the emergency 80 exhaust of the air-brake system, to thereby utilize the air that is exhausted when the emergency brake is applied for actuating said motor.

In testimony whereof I hereunto affix my 90 signature.

ROBERT C. BROOKS.
